CLAIM

The ornamental design for a stove, as shown and described.

DESCRIPTION

FIG. 1 is a first upper perspective view of a stove design; FIG. 2 is a second upper perspective view of the stove design of FIG. 1;

FIG. 3 is a front view of the stove design of FIG. 1;

FIG. 4 is a top view of the stove design of FIG. 1;

FIG. 5 is a first side view of the stove design of FIG. 1; and,

FIG. 6 is a second side view of the stove design of FIG. 1. The broken line disclosure represents unclaimed portions or unclaimed boundaries of the stove in which the design is embodied.
